UNITED STATES PATENT OFFICE

CHARLES H. LAY, OF PITTSBURGH, PENNSYLVANIA, ASSIGNOR TO THE UNION SWITCH & SIGNAL COMPANY, OF SWISSVALE, PENNSYLVANIA, A CORPORATION OF PENNSYLVANIA

RAILWAY TRAFFIC CONTROLLING APPARATUS

Application filed October 23, 1930. Serial No. 490,678.

My invention relates to railway traffic controlling apparatus, and particularly to apparatus of the type comprising a traffic controlling device controlled by a manually operable lever through the medium of a valve and a fluid pressure motor.

One object of my invention is the provision, in apparatus of the type described, of means for limiting the movement of the lever unless both the valve and the traffic controlling device are in predetermined relative positions.

I will describe three forms of railway traffic controlling apparatus embodying my invention, and will then point out the novel features thereof in claims.

In the accompanying drawings, Fig. 1 is a view, partly diagrammatic, illustrating one form of railway traffic controlling apparatus embodying my invention. Figs. 2 and 3 are views showing modified forms of parts of the apparatus shown in Fig. 1 and also embodying my invention.

Similar reference characters refer to similar parts in all three views.

Referring first to Fig. 1, the reference characters 1 and 1^a designate the rails of a stretch of railway track provided with a switch 2 of the usual and well known form. This switch 20 is operated by a fluid pressure motor A comprising a cylinder 3 containing a reciprocable piston 4. Attached to the piston 4 is a piston rod 5 which is operatively connected with the movable points of the switch 2 through suitable mechanism which is indicated by the dotted line 5^a.

The motor A is controlled by a switch valve C comprising a slide valve 7 operating in a valve chamber 6. The chamber 6 is constantly supplied with fluid pressure, from a source not shown in the drawings, through pipe 11. When the slide valve is in its normal position, fluid pressure is supplied from chamber 6, through pipe 10 to the lower end of cylinder 3 of motor A, and the upper end of this cylinder is connected with atmosphere through pipe 8 and port 9. With the valve in this position, therefore, the piston 4 is moved upwardly and the switch then occupies its normal position. When the slide valve 7 occu-

pies its reverse position, pipe 8 is connected with chamber 6, and pipe 10 is connected through port 9 to atmosphere. The piston 4 is then driven downwardly and the switch 2 is moved to its reverse position.

The valve 7 is provided with two spaced notches 15 and 16 one or the other of which receives a locking rod 17 according as the valve is in the reverse or normal position. The rod 17 carries an armature 18 associated with a winding 19, and is constantly urged toward the slide valve 7 by a spring 20. When winding 19 is energized, however, armature 18 is moved outwardly, thereby disengaging the rod 17 from the notch in the slide valve 65 and permitting the valve to be shifted by means which I will describe hereinafter. It will be plain, however, that the valve can be shifted only when winding 19 is energized to draw the rod 17 out of the notch in the valve. 70

The switch valve C also comprises two oppositely disposed axially aligned cylinders 12 and 12^a. The cylinder 12 contains a piston 13 carrying a stem 14 which engages one end of the slide valve 7, and the cylinder 12^a contains a piston 13^a carrying a stem 14^a which engages the other end of the slide valve 7. Cylinder 12 is at times supplied with fluid pressure by a valve 21 comprising a valve stem 23 provided with a winding 25 and an armature 24 associated therewith. When winding 25 is deenergized the valve stem 23 occupies its left-hand position and cylinder 12 is connected with atmosphere. When winding 25 of valve 21 is energized, however, the valve stem 23 is moved to the right and cylinder 12 is then disconnected from atmosphere and is connected with a source of fluid pressure. In similar manner, a valve 22 controls the supply of fluid pressure to cylinder 12^a so that when winding 25^a of valve 22 is deenergized, cylinder 12^a is connected with atmosphere, but that when this winding is energized cylinder 12^a is supplied with fluid pressure. It will be plain from the drawings that when cylinder 12^a is supplied with fluid pressure, piston 13^a is moved upwardly to drive the valve 7 to its normal position. When cylinder 12 is supplied with fluid pressure, however, piston 13 moves 100

95

100

downwardly and drives the valve 7 to its reverse position. In either case, of course, movement of valve 7 is possible only if the locking rod 17 is withdrawn from the notch 15 or 16.

6 The windings 25 and 25^a of valves 21 and 22 and winding 19 are controlled by a manually operable lever L. This lever comprises a handle 33 and a plurality of contacts ar-

10 ranged to be open or closed in accordance with the position occupied by this handle. The diagram appearing immediately below the handle 33 in Fig. 1 illustrates the principal positions which may be occupied by the

15 lever. These positions are: full normal or left-hand position N, full reverse or right-hand position R, and two intermediate positions known as the reverse indicating position D and the normal indicating position B. The various contacts are designated by 20 the reference characters which correspond to this diagram and which indicate the positions in which the associated contacts are closed. For example, the lowest contact on 25 the lever L is designated by the reference character NB, which means that this contact is closed when the lever L is in the normal position, the B position, or any position between these two.

30 The circuit for winding 19 may be traced from a suitable source of current, such as a battery P, through wire 37, wire 66, contact BD of lever L, wire 67, winding 19, wire 68, wire 69, and wire 38 back to battery P.

35 The circuit for winding 25 of valve 21 passes from wire 37, through wires 66 and 70, contact DR of lever L, wire 71, winding 25 of valve 21 and wire 69 to wire 38. When contact NB of lever L is closed, current flows

40 from wire 37, through wires 66 and 72, contact NB of lever L, wire 73, winding 25^a of valve 22, wire 74 and wire 69 to wire 38.

Associated with lever L are a normal indication lock K and a reverse indication lock 45 J. Each of these indication locks comprises a segment 36 operatively connected with the lever L, and a magnet 34 having a locking dog 35 controlled thereby. Segment 36 of lock K is provided with a projection 36^a so 50 arranged that when the lever is moved from the reverse position toward the normal position, the dog 35 engages the projection 36^a and prevents movement of the lever past the normal indicating position B unless magnet 55 34 is energized. In similar manner, segment 36 of lock J is provided with a projection 36^b which is arranged to be engaged by a dog 35 at the D position when the lever is moved from the normal position toward the reverse 60 position, unless the magnet 34 is energized. The magnets 34 of the indication locks K and J are controlled by a polarized indication relay E, and by contacts on the lever L. The circuit for the magnet of lock K passes from

65 wire 37, through wire 55, front contact 56 of

relay E, wire 57, normal contact 58 of relay E, wire 59, contact RB of lever L, wire 60, magnet 34 of lock K, and wire 62 to wire 38. The reverse locking circuit passes from wire 37, through wire 55, front contact 56 70 of relay E, wire 57, reverse contact 63 of relay E, wire 64, contact ND of lever L, wire 65, magnet 34 of lock J, wire 61, and wire 62 to wire 38.

The apparatus thus far referred to is described and illustrated in United States Letters Patent No. 1,713,169, granted to J. P. Coleman on the 14th day of May, 1929, for railway traffic controlling apparatus.

75 The relay E is controlled by two circuit controllers G^a and H^a. Circuit controller G^a comprises two movable contact fingers 29 and 48 connected with the slide valve 7 through a suitable means indicated by the dash line 7^a. When the slide valve 7 is in its normal position, contact fingers 29 and 48 occupy the positions shown in the drawings, so that contacts 27^a—29 and 28—48, respectively, are closed. When the slide valve 7 is in its reverse position, contact fingers 29 80 and 48 occupy their reverse positions so that contacts 27—29 and 28^a—48 are closed.

85 The circuit controller H^a comprises three movable contact fingers 30, 31 and 32 connected with the switch 2 through a suitable means indicated by the dash line 5^a. When the switch 2 occupies its normal position, contacts 30—45 and 31—44 are closed and contact 32—52 is open. When the switch 2 occupies its reverse position, contacts 30—43 90 and 31—46 are closed, and contact 32—52 is open. Contact 32—52 is closed at all times except when the switch 2 is in the extreme normal or extreme reverse position.

95 When slide valve 7 and switch 2 are in their normal positions, the circuit for relay E is from one terminal of battery P, through wire 37, wire 39, wire 26, contact 28, contact 48, wire 42, contact 31, wire 44, wire 43, winding of relay E, wire 51, contact 27^a, contact 29, wire 41, contact 30, wire 45, wire 47, and wire 38 back to the other terminal of battery P. Relay E is then energized in the normal direction so that its contacts 56 and 58 are closed. When slide valve 7 and switch 2 are in their reverse positions, the circuit for relay E will be from one terminal of battery P, through wire 37, wire 39, wire 46, contact 31, wire 42, contact 48, contact 28^a, wire 50, wire 49, wire 51, winding of relay E, wire 43, contact 30, wire 41, contact 29, contact 27, wire 40, wire 47, and wire 38 back to the other terminal of battery P. Relay E will then be energized in the reverse direction so that its contacts 56 and 63 are closed. When switch 2 is in any intermediate position, relay E will be shunted through contact 32—52, and both terminals of battery P will be disconnected from relay E. The shunting circuit will be from the

winding of relay E, through wire 51, wire 49, contact 32, wire 52, and wire 43 back to the winding of relay E.

If slide valve 7 is in the normal position and switch 2 is in the reverse position, relay E will be shunted through contacts 27^a—29 and 30—43, and both terminals of battery P will be disconnected from relay E. The shunting circuit will be from the winding of relay E, through wire 51, contact 27^a, contact 29, wire 41, contact 30, and wire 43 back to the winding of relay E. If slide valve 7 is in the reverse position and switch 2 is in the normal position, relay E will be shunted through contacts 28^a—48 and 31—44, and both terminals of battery P will be disconnected from relay E. The shunting circuit will be from the winding of relay E, through wire 51, wire 49, wire 50, contact 28^a, contact 48, wire 42, contact 31, wire 44, and wire 43 back to the winding of relay E.

As shown in the drawings, the lever L occupies the normal position, so that winding 25^a of valve 22 is energized. Cylinder 12^a is therefore supplied with fluid pressure, and valve 7 occupies its normal position. Contact BD of lever L is open so that winding 19 is deenergized, and rod 17 projects into groove 16 to lock the slide valve in position. Contact DR of lever L is also open so that winding 25 of valve 21 is deenergized. Since valve 7 is in its normal position, fluid pressure is supplied to the lower end of cylinder 3 of motor A, and switch 2 occupies its normal position. Since the slide valve 7 and the switch 2 both occupy their normal positions, relay E is energized in the normal direction. The circuit for magnet 34 of lock K is open at contact RB of lever L, and the circuit for magnet 34 of lock J is open at reverse contact 63 of relay E.

In explaining the operation of the apparatus, I will assume that the operator in charge of lever L wishes to reverse switch 2. Lever L is first moved toward the reverse position. Magnet 34 of the reverse indication lock J is deenergized, however, so that the movement of the lever is arrested at the D position. The movement of the lever from the N to the D position deenergizes winding 25^a of valve 22, and energizes winding 25 of valve 21. Cylinder 12 is therefore supplied with fluid pressure and cylinder 12^a is connected with atmosphere. The closing of contact BD of lever L also completes the circuit for winding 19 so that the rod 17 is drawn out of groove 16 in slide valve 7, and the valve is therefore moved to its reverse position by piston 13. The reversal of slide valve 7 connects the lower end of cylinder 3 with atmosphere and supplies fluid pressure to the upper end of this cylinder. The switch 2 is therefore moved to its reverse position. When the switch has attained its full reverse position, circuit controllers G and H will complete the

reverse circuit for relay E. The closing of reverse contact 63 of relay E will complete the circuit for magnet 34 of lock J. Dog 35 of this lock is therefore lifted to permit the movement of lever L to be completed to its full reverse position R. As a result of this movement of lever L, contacts ND and BD will become opened; the opening of contact ND will deenergize the magnet 34 of lock J, and the opening of contact BD will deenergize winding 19 so that rod 17 will enter groove 15 to lock the slide valve in its reverse position. Winding 25 of valve 21 will remain in its energized condition, however, because contact DR will remain closed.

If the operator wishes to restore the switch to its normal position, he will first move the lever L from the reverse position to the normal indicating position B where the lever will be locked against further movement by engagement of dog 35 of lock J with projection 35^a of segment 36. With the lever L in the B position, winding 19 will be energized so that the rod 17 will be withdrawn from slot 15 in the valve 7, winding 25 of valve 21 will be deenergized, and winding 25^a of valve 22 will be energized. The slide valve 7 will therefore be restored to its normal position. As a result of this movement of valve 7, the piston 4 of motor A will move to its normal position, thereby driving the switch 2 to its normal position. With the slide valve 7 and the switch 2 both occupying their normal positions the normal circuit for relay E will be closed, so that contact 58 will be closed. Contact RB of lever L is already closed, so that current will now be supplied to magnet 34 of lock K. Dog 35 of this lock is therefore lifted out of engagement with the projection 36^a of segment 36 and the operator can complete the movement of the lever L to the full normal position. The consequent opening of contact BD deenergizes winding 19 and allows rod 17 to enter groove 16 in the slide valve 7 to lock the valve in its normal position.

Fig. 2 shows a system for controlling indicating relay E when a plurality of switches are controlled by one lever.

Indicating relay E is controlled by circuit controllers G^a, H^a, G^b, H^b, G^c and H^c. Circuit controller G^a and H^a are similar to those in Fig. 1 and are connected through suitable means designated by dash lines 7^a and 5^a to the first slide valve and first switch, respectively, as shown in Fig. 1. Circuit controller G^b comprises two movable contact fingers 77 and 78, connected to the slide valve of the second switch through suitable means designated by a dash line 7^b. When the second slide valve occupies its normal position, contact fingers 77 and 78 occupy the positions shown on the drawings, so that contacts 75—77 and 76—78, respectively, are closed. When the second slide valve is in its reverse

position, contact fingers 77 and 78 occupy their reverse positions so that contacts 75^a—77 and 76^a—78, respectively, are closed. Circuit controller H^b comprises four movable contact fingers 80, 84, 86 and 90 connected to the second switch through suitable means designated by a dash line 5^b. When the second switch occupies its normal position, contact fingers 80, 84, 86 and 90 occupy the positions shown on the drawings and contacts 80—92, 84—26 and 86—113 are closed. When the second switch occupies its reverse position, contact fingers 80, 84, 86 and 90 occupy their reverse positions and contacts 80—40, 84—87 and 90—45 are closed. When the second switch occupies any intermediate position, contacts 86—88 and 90—91 are closed. Circuit controller G^c comprises two contact fingers 94 and 99 connected to the slide valve of the third switch through suitable means designated by a dash line 7^c. When the third slide valve occupies its normal position, contact fingers 94 and 99 occupy the positions shown on the drawings and contacts 93—94 and 100—99 are closed. When the third slide valve occupies its reverse position, contact fingers 94 and 99 occupy their reverse positions and contacts 93^a—94 and 100^a—99 are closed. Circuit controller H^c comprises four contact fingers 104, 103, 102 and 105, connected to the third switch through suitable means designated by a dash line 5^c. When the third switch occupies its normal position, contact fingers 104, 103, 102 and 35 105 occupy the positions shown on the drawings and contacts 104—47, 103—82 and 102—106 are closed. When the third switch occupies its reverse position, contact fingers 104, 103, 102 and 105 occupy their reverse positions and contacts 104—81, 103—39 and 40 105—92 are closed. When the third switch occupies any intermediate position contacts 102—107 and 105—109 are closed.

When the switches and slide valves are all in normal positions, all the contacts are in the positions shown on the drawings, and the relay circuit is from wire 47, through contact 104, wire 95, contact 94, contact 93, wire 110, wire 92, contact 80, wire 79, contact 77, 45 contact 75, wire 111, wire 45, contact 30, wire 41, contact 29, contact 27^a, wire 51 winding of relay E, wire 43, wire 44, contact 31, wire 42, contact 48, contact 28, wire 26, contact 84, wire 83, contact 78, contact 76, wire 82, contact 103, wire 98, contact 99, contact 100 and wire 97 to wire 39. When the switches and slide valves are all in the reverse positions, the relay circuit will be from wire 47 through wire 96, contact 93^a, contact 94, wire 95, contact 104, wire 81, contact 75^a, contact 77, wire 79, contact 80, wire 40, contact 27, contact 29, wire 41, contact 30, wire 43, winding of relay E, wire 51, wire 49, wire 50, contact 28^a, contact 48, wire 42, contact 31, wire

46, wire 85, contact 76^a, contact 78, wire 83, contact 84, wire 87, wire 101, contact 100^a, contact 99, wire 98 and contact 103 to wire 39. Wires 39 and 47 are connected across a suitable source of current as shown in Fig. 1.

If the first slide valve and switch do not correspond in position, the relay E will be shunted and disconnected from the source of current as in Fig. 1. If the first slide valve and first switch are in normal positions, the second slide valve is in normal or reverse position, and the second switch is in reverse position, relay E will be shunted through contact 45—90, and both terminals of relay E will be disconnected from the source of current. The shunting circuit will be from the winding of relay E, through wire 51, contact 27^a, contact 29, wire 41, contact 30, wire 45, contact 90, wire 89, wire 26, contact 28, contact 48, wire 42, contact 31, wire 44 and wire 43 back to the winding of relay E. If the first slide valve and first switch are in normal positions, the second slide valve is in reverse position, and the second switch is in normal position, both terminals of relay E will be disconnected from the source of current. If the first slide valve and first switch are in reverse positions, the second slide valve is in normal or reverse position, and the second switch is in normal position, relay E will be shunted through contact 86—113, and both terminals of relay E will be disconnected from the source of current. The shunting circuit will be from the winding of relay E, through wire 51, wire 49, wire 50, contact 28^a, contact 48, wire 42, contact 31, wire 46, contact 86, wire 113, wire 40, contact 27, contact 29, wire 41 contact 30 and wire 43 back to the winding of relay E. If the first slide valve and first switch are in reverse positions, the second slide valve is in normal position, and the second switch is in reverse position, both terminals of relay E will be disconnected from the source of current. If the first switch and first slide valve are in normal positions, while the second slide valve is in normal or reverse position and the second switch is in any intermediate position, the relay E will be shunted through contact 90—91. The shunting circuit will be from the winding of relay E, through wire 51, contact 27^a, contact 29, wire 41, contact 30, wire 45, contact 91, contact 90, wire 89, wire 26, contact 28, contact 48, wire 42, contact 31, wire 44 and wire 43 back to the winding of relay E. If the first slide valve and first switch are in reverse positions, the second slide is in normal or reverse position, and the second switch is in any intermediate position, the relay E will be shunted through contact 86—88 and both terminals of relay E will be disconnected from the source of current. The shunting circuit will be from the winding of relay E, through wire 51, wire 49, wire 50, contact 28^a, contact 48, wire 42, contact 31, wire 46, 130

contact 86, contact 88, wire 113, wire 40, contact 27, contact 29, wire 41, contact 30 and wire 43 back to the winding of relay E. If the first slide valve and first switch are in 5 normal positions, the second switch and second slide valve are in normal positions, the third slide valve is in normal or reverse position, and the third switch is in reverse position, the relay E will be shunted through 10 contact 105—92 and both terminals of relay E will be disconnected from the source of current. The shunting circuit will be from the winding of relay E, through wire 51, contact 27^a, contact 29, wire 41, contact 30, wire 15 45, wire 111, contact 75, contact 77, wire 79, contact 80, wire 92 contact 105 wire 108, wire 82, contact 76, contact 78, wire 83, contact 84, wire 26, contact 28, contact 48, wire 42, contact 31, wire 44 and wire 43 back to the winding of relay E. If the first slide valve first 20 switch, second slide valve, and second switch, are all in normal positions, while the third slide valve is in reverse position and the third switch is in normal position, both terminals of relay E will be disconnected from the source of current. If the first switch, 25 first slide valve, second switch, and second slide valve are all in the reverse positions, while the third slide valve is in normal or reverse position and the third switch is in normal position, the relay E will be shunted through contact 102—106. The shunting circuit will be from the winding of relay E, through wire 51, wire 49, wire 50, contact 30, 30 28^a, contact 48, wire 42, contact 31, wire 46, wire 85, contact 76^a, contact 78, wire 83, contact 84, wire 87, contact 102, wire 106, wire 81, contact 75^a, contact 77, wire 79, contact 80, wire 40, contact 27, contact 29, wire 41, contact 30, and wire 43 back to the winding of relay E. If the first slide valve, first 35 switch, second slide valve, and second switch are all in reverse positions, while the third slide valve is in normal position and the third switch is in reverse position, both terminals of the relay E will be disconnected from the source of current. If the first switch, first slide valve, second switch, and second slide valve are all in normal positions, while the third slide valve is in normal position and the third switch is in reverse position, both terminals of the relay E will be disconnected from the source of current. If the first switch, first slide valve, second switch, and second slide valve are all in normal positions, while the third slide valve is in normal or reverse position and the third switch is in any intermediate position, the relay E will be shunted through contact 109—105. The shunting circuit will be from the winding of relay E, 40 45 through wire 51, contact 27^a, contact 29, wire 41, contact 30, wire 45, wire 111, contact 75, contact 77, contact 79, contact 80, wire 92, contact 109, contact 105, wire 108, wire 82, contact 76, contact 78, wire 83, contact 84, wire 46, contact 28, contact 48, wire 42 contact 31, wire 44, and wire 43 back to the winding of relay E. If the first slide valve and first switch are in reverse positions, the second slide valve and second switch are in reverse 45 50 positions, the third slide valve is in normal or reverse position, and the third switch is in any intermediate position, the relay E will be shunted through contact 102—107 and both terminals of relay E will be disconnected from the source of current. The shunting circuit will be from the winding of relay E, through wire 51, wire 49, wire 50, contact 28^a, contact 48, wire 42, contact 31, wire 46, wire 85, contact 76^a, contact 78, wire 83, contact 84, wire 87, contact 102, contact 107, wire 106, wire 81, contact 75^a contact 77, wire 79, contact 80, wire 40, contact 27, contact 29, wire 41, contact 30 and wire 43 back to the winding of relay E.

Fig. 3 illustrates a switch indication circuit for a crossover having no contacts operated by the slide valves. The indicating relay E is controlled by circuit controllers H^a and H^b. Contact fingers 114, 115 and 116 of circuit controller H^a are controlled by the first switch through suitable means represented by dash line 5^a, and contact fingers 123, 124 and 125 of circuit controller H^b are controlled by the second switch through suitable means represented by dash line 5^b. Contacts 47—114 and 51—115 are closed in the normal position of the first switch, while contacts 132—114 and 39—115 are closed in the reverse position of this switch. Contact 116—119 is closed in all intermediate positions of the switch. Contacts 123—43 and 124—39 are closed in the normal position, and contacts 123—47 and 124—131 are closed in the reverse position, of the second switch, while contacts 123—128, 124—129 and 125—130 are closed in all intermediate positions of this switch.

The normal circuit for relay E is from wire 47, through contact 114, wire 120, contact 123, wire 43, winding of relay E, wire 51, contact 115, wire 121, contact 124 and wire 39. The reverse circuit for relay E is from wire 47, through contact 123, wire 120, contact 114, wire 132, wire 51, winding of relay E, wire 43, wire 131, contact 124, wire 121, contact 115 and wire 39. When the first switch is in any intermediate position, relay E will be shunted through contact 116—119, and both terminals of the relay will be disconnected from the source of current. The shunting circuit will be from the winding of relay E, through wire 51, wire 118, contact 119, contact 116, wire 117, and wire 43 back to the winding of relay E. If the first switch is in the normal position while the second switch is in any intermediate position, relay E will be shunted through contacts 124—129 and 130—125. The shunting circuit will be from winding of relay E, through wire 51, contact 115, wire 121, contact 124, contact 129, wire 127, wire 126, contact 130, contact 125, wire 122 and wire 43 back to the winding of relay E. If the first switch is in the reverse position while the second switch is in any intermediate position, relay E will be shunted

through contacts 123—128 and 125—130. The shunting circuit will be from the winding of relay E, through wire 51, wire 132, contact 114, wire 120, contact 123, contact 128, wire 126, contact 130, contact 125, wire 122 and wire 43 back to the winding of relay E. If the first switch is in normal position and the second switch is in reverse position, relay E will be shunted through contacts 51—115 and 124—131 and both terminals of relay E will be disconnected from the source of current. The shunting circuit will be from the winding of relay E, through wire 51, contact 115, wire 121, contact 124, wire 131 and wire 43 back to the winding of relay E. If the first switch is in the reverse position and the second switch is in the normal position, relay E will be shunted through contacts 132—114 and 123—43, and both terminals of relay E will be disconnected from the source of current. The shunting circuit will be from the winding of relay E, through wire 51, wire 132, contact 114, wire 120, contact 123 and wire 43 back to the winding of relay E.

Although I have herein shown and described only three forms of apparatus embodying my invention, it is understood that various changes and modifications may be made therein within the scope of the appended claims without departing from the spirit and scope of my invention.

Having thus described my invention, what I claim is:

35. 1. In combination, a railway track switch, a fluid pressure cylinder for operating said switch, a slide valve having a normal and a reverse position, means including said slide valve for supplying fluid pressure to one end of said cylinder or the other, means including a manually operable lever for shifting said slide valve to normal and reverse positions, an indicating relay controlled by said switch and said slide valve, means for preventing said relay from being energized in the normal direction unless said slide valve is in the normal position, and means for preventing said relay from being energized in the reverse direction unless said slide valve is in the reverse position, an indicating relay controlled by said switch and said slide valve, means for preventing said relay from being energized in the normal direction unless said slide valve is in the normal position, and means for preventing said relay from being energized in the reverse direction unless said slide valve is in the reverse position, means for shunting said relay and completely disconnecting the supply of current from said relay when said switch and slide valve do not correspond in position, and means for preventing said lever from being moved to the full normal or reverse position unless said relay is energized in the normal or reverse direction.

60. 2. In combination, a railway track switch, a fluid pressure cylinder for operating said switch, a slide valve having a normal and a reverse position, means including said slide valve for supplying fluid pressure to one end of said cylinder or the other, means including a manually operable lever for shifting

ing said slide valve to normal and reverse positions, an indicating relay controlled by said switch and said slide valve, means including a first and a second circuit controller for preventing said relay from being energized in the normal direction unless said switch and slide valve are both in normal positions, means including said first and second circuit controllers for preventing said relay from being energized in the reverse direction unless said switch and slide valve are both in reverse positions, means including said first and second circuit controllers for completely disconnecting the supply of current from said relay when said switch and slide valve do not correspond in position, two normal contacts included in said first circuit controller and two normal contacts included in said second circuit controller for closing the normal circuit of said relay, two reverse contacts in said first circuit controller and two reverse contacts in said second circuit controller for closing the reverse circuit of said relay, an intermediate contact included in said second circuit controller for shunting said relay when said switch is in any intermediate position and said slide valve is in any position, means including a normal contact of said first circuit controller and a reverse contact of said second circuit controller for shunting said relay when said slide valve is in the normal position and said switch is in the reverse position, means including a reverse contact of said first circuit controller and a normal contact of said second circuit controller for shunting said relay when said slide valve is in a reverse position and said switch is in a normal position, and means for preventing said lever from being moved to the full normal or reverse position unless said relay is energized in the normal or reverse direction.

3. In combination, a plurality of railway track switches, a plurality of fluid pressure cylinders for operating said switches, a plurality of slide valves one for each of said cylinders each having a normal and a reverse position, means controlled by each of said slide valves for supplying fluid pressure to one end or the other of the corresponding cylinders, means including a manually operable lever for shifting said plurality of slide valves to normal and reverse positions, an indicating relay controlled by said plurality of switches and said plurality of slide valves, means for preventing said relay from being energized in the normal direction unless said switches and said slide valves are all in normal positions, means for preventing said relay from being energized in the reverse direction unless said switches and said slide valves are all in reverse positions, means for shunting said relay and completely disconnecting the supply of current from said relay when said switches and said

- slide valves do not correspond in positions, and means for preventing said lever from being moved to the full normal or reverse position unless said relay is energized in the 5 normal or reverse direction.
4. In combination, a plurality of railway track switches, a plurality of fluid pressure cylinders for operating said switches, a plurality of slide valves one for each of said 10 cylinders each having a normal and a reverse position, means controlled by each of said slide valves for supplying fluid pressure to one end or the other of the corresponding cylinders, means including a manually operable lever for shifting said plurality of slide valves to normal and reverse positions, an indicating relay controlled by said plurality of switches and said plurality of slide valves, means for preventing said relay from 15 being energized in the normal direction unless said switches and said valves are all in normal positions, means for preventing said relay from being energized in the reverse direction unless said switches and said slide valves are all in reverse positions, means including a plurality of first and second circuit controllers for completely disconnecting the supply of current from said relay when said switches and slide valves do not 20 correspond in positions, two normal contacts of each of said plurality of first circuit controllers, and two normal contacts of each of said plurality of second circuit controllers for closing the normal circuit of said relay, two reverse contacts of each of said plurality of first circuit controllers and two reverse contacts of each of said plurality of said second circuit controllers for closing the reverse circuit of said relay, a contact of a second 25 circuit controller of said plurality of second circuit controllers closed in all positions except the reverse position of a second switch of said plurality of switches for shunting said relay when the first slide valve and switch and the second slide valve do not correspond to the position of said second switch, a contact of a second circuit controller of said plurality of second circuit controllers closed in all positions except the normal position of a second switch of said plurality of switches for shunting said relay when the first slide valve and switch and the second slide valve do not correspond to the position of said second switch, a contact of a third circuit controller of said plurality of second circuit controllers closed in all positions except the reverse position of a third switch of said plurality of switches for shunting said relay when the first slide valve and switch and the second slide valve and the third slide valve do not correspond to the position of said third switch, a contact of a third circuit controller of said plurality of second circuit controllers closed in all positions except the normal position of a third 30 switch of said plurality of switches for shunting said relay when the first slide valve and switch and the second slide valve and switch and the third slide valve do not correspond to the position of said third switch, and means for preventing said lever from being moved to the full normal or reverse position unless said relay is energized in the normal or reverse direction.
5. In combination, a first and a second railway track switch, means including a manually operable lever for shifting said switches to normal and reverse positions, a first circuit controller operatively connected with said first switch having two normal contacts 35 and two reverse contacts and an intermediate contact, a second circuit controller operatively connected with said second switch and having two contacts each closed in the normal position and the reverse position and in all intermediate positions except in a position adjacent said normal position and in a position adjacent said reverse position and an intermediate contact, an indicating relay, means including said normal contacts of said first circuit controller and the normal contacts of said second circuit controller for closing the normal circuit of said relay, means including said reverse contacts of said first circuit controller and the reverse contacts of said second circuit controller for closing the reverse circuit of said relay, means including said intermediate contact of said first circuit controller for shunting said relay when said first switch is in any intermediate position, means including two intermediate contacts of said second circuit controller for shunting said relay when said first switch is in a normal position and said second switch is in any intermediate position, means including two intermediate contacts of said second circuit controller for shutting said relay when said first switch is in a reverse position and said second switch is in any intermediate position, and means for preventing said lever from being moved to the full normal or reverse position unless said relay is energized in the normal or reverse direction.
- In testimony whereof I affix my signature.
